RADIO CABINET WITH MULTIPLE ADJUSTABLE SPEAKERS

Donald K. Eaton, Los Angeles, Calif.

Application May 15, 1956, Serial No. 41,492

Term of patent 14 years

(Cl. D56—4)

FIG. 3

Figure 1 is a front elevational view of a radio cabinet with multiple adjustable speakers showing my new design;

Figure 2 is a side elevational view; and

Figure 3 is a top plan view.

I claim:

The ornamental design for a radio cabinet with multiple adjustable speakers, as shown.
